INFANT'S TOY ANIMAL FIGURE OR SIMILAR ARTICLE

Naomi V. Simmons, Dallas, Tex.

Application January 16, 1950, Serial No. 7,270

Term of patent 7 years

(Cl. D34—15)

To all whom it may concern:

Be it known that I, Naomi V. Simmons, a citizen of the United States, residing at Dallas, in the county of Dallas and State of Texas, have invented a new, original and ornamental Design for an Infant's Toy Animal Figure or similar article, of which the following is a specification, reference being had to the accompanying drawing, forming part thereof:

I claim:

The ornamental design for an infant's toy animal figure or similar article, substantially as shown.

NAOMI V. SIMMONS.
